UNITED STATES PATENT OFFICE

THOMAS MANEY, OF LOUISVILLE, KENTUCKY

LUBRICATING DEVICE

Application filed February 29, 1928. Serial No. 253,020.

This invention relates to an improvement in lubricating devices.

The object of the invention is to lubricate the inner side of the outer railroad rail around curves to prevent excessive wear between the rail head and the wheel flanges. A great many different lubricating devices have been tried for this very old problem but none of them have been successful and these rails 10 are still usually lubricated by smearing grease onto rails by hand brush or paddle.

It is only necessary to lubricate the inner surface of the head of the outer rail around the curve, and in fact this is all that should 15 be lubricated. By the manual means mentioned, the grease is spread over the top of the rail, where it destroys the tractive power, and for this reason the method is objectionable as well as wasteful and laborious.

20 When the grease is applied to the wheel flanges or to the wheels themselves, which are rotated at high speed, the application is difficult and uncertain, and even when successfully deposited the lubricant is thrown off by centrifugal force or dissipated by atmospheric friction and often deposited on the brake shoes or the top of the rail, to the detriment of both braking power and tractive force, thereby involving a certain element of danger. Little of the lubricant actually reaches the only place where it is required, namely, the inner side of the rail head 25 of the outer rail of the curve.

30 This invention obviates these objections by providing a very simple device for applying lubricant directly to the stationary surface of the rail at such points and may be operated by an attendant who walks along the track holding the device in contact with the rail and moving it therealong, by reason of which the lubricant is automatically applied to the inner surface only of the rail head of the outer rail of the curve.

35 It is simple in construction and use and 40 contains a sufficient amount of lubricant to cover one and a half miles of rail and only weighs three pounds. Graphite sticks or cartridges are preferably used in the device. These being in solid form may be easily applied thereto and a sufficient quantity of the

graphite sticks may be carried in the pocket of the operator to recharge the lubricator several times.

In the accompanying drawings:

Fig. 1 is a side perspective view of the 55 device;

Fig. 2 is a perspective view approximately at right angles thereto, showing a portion in section;

Fig. 3 is a top perspective view of the 60 same;

Fig. 4 is a detail sectional view through the end of the handle; and

Fig. 5 and 6 are side and top views of the 65 lubricating device in use.

The lubricating device is intended to lubricate only the inner surface of the head of the outer rail around a curve, and in the drawings the rail is designated by the numeral 1.

A guide 2 is intended to slide on the upper surface of the rail head and has a flange 3 extending upwardly therefrom and held within a clamp 4 by means of a thumb screw 5. The clamp 4 has a collar 6 connected therewith, which receives a tubular handle 7. Said tubular handle extends through the collar 6 and has a mitered inner end 8. An axle 9 is also carried by the clamp 4 and carries a guide wheel 10 in position to roll along the inner surface of the head of the rail 1.

The tubular handle 7 is adapted to contain the sticks or cartridges 11 of hard graphite preferably, although other lubricants might be used. The sticks of graphite 11 are inserted into the tubular handle 7 throughout the major portion of the length thereof, but behind the sticks, and acting thereon is a metal plunger 12 providing a uniform pressure on the sticks of graphite by gravity, this plunger being slidably mounted freely in the tubular handle 7. A cap 13 closes the outer end of the handle 7.

The sticks or cartridges of graphite or other lubricating material are inserted into the tubular handle 7, after which the plunger 12 is inserted in the upper end to exercise uniform pressure on the sticks to give them the desired abrasive effect on the inner surface of the rail head. The sticks of lubricating material are forced downwardly by this 100

plunger as they are worn away and a protruding end is kept in contact with the rail head at the lower end of the tubular handle 7. The guide plate 2 is placed over the rail head with the guide wheel 10 in contact with the inner surface thereof and the lubricating device is then pushed forward along the rail, leaving a closely adhering streak of the lubricant in the exact position desired, namely on the inner surface of the head of the outer rail around a curve.

10 The lubricant thus deposited on the rail head does not flow over the rail and is not transmitted by the wheels of the train to surfaces where it may be harmful or undesirable.

15 The lubricant in solid form provides less waste, can be placed exactly where desired, and being abraded upon the rail surface it is more tenacious than oil or fluid grease.

20 The lubricating device is adapted to either rail and may be reversed for use on either the right or left rail by merely loosening the thumb screw 5, so as to slightly release the collar 6 on the handle 7 and by giving this handle a half turn in the collar it occupies a similar position in relation to the opposite rail. The mitered lower end of the tubular handle supports the sticks of lubricant in close proximity to the rail head so as to prevent destruction to the sticks except by the abrasion thereof against the rail head.

25 A spring catch 14 may be attached to the plate 2 to hold the charge of lubricant in place when the device is not in use.

30 I claim:—

35 1. A lubricating device of the character described including a handle, a clamp connected with the handle, a guide plate secured to the clamp for overlapping a rail head, and a guide wheel carried by the clamp in position to engage the inner surface of the rail head.

40 2. A lubricating device of the character described including a tubular handle having a mitered discharge end for the discharge of a lubricant onto a rail head, a clamp connected with the handle, a guide plate in position to fit over the rail head and having a flange for connecting said plate with the clamp, and a guide wheel carried by the clamp for engaging the inner surface of the rail head.

45 3. A lubricating device of the character described including a guide plate, a clamp connected therewith, and a tubular handle extending through the clamp and into position beneath the plate to supply lubricant to the side of a rail.

50 4. A lubricating device of the character described including a guide plate, a clamp connected therewith, and a tubular handle extending through the clamp and into position beneath the plate to supply lubricant to the side of a rail, and a guide carried by the clamp in position to engage the inner surface of the rail.

55 5. A lubricating device of the character de-

scribed comprising a guide adapted to ride on the top surface of a rail, a tubular member connected with said guide and extending into a position to supply lubricant in solid form directly onto the side of the rail, said tubular member being of approximately uniform size throughout and adapted to be used as a handle.

6. A lubricating device of the character described comprising a guide adapted to ride on the top surface of a rail, a tubular member connected with said guide and having an open end in position to supply lubricant in solid form directly onto the side of the rail, said tubular member being of approximately uniform size throughout from said open end outwardly, the outer end being adapted to be used as a handle.

7. A lubricating device of the character described comprising a guide, a clamp connected therewith, and a handle member having a source of lubricant connected therewith and extending through the clamp and into position beside the guide and a rail to supply lubricant to said rail.

90 In testimony whereof I affix my signature.
THOMAS MANEY.
